UNITED STATES PATENT OFFICE.

CARL ABERNATHY, OF ATLANTA, GEORGIA.

TOY SWING.

1,277,814.

Specification of Letters Patent. Patented Sept. 3, 1918.

Application filed November 16, 1917. Serial No. 202,386.

To all whom it may concern:

Be it known that I, CARL ABERNATHY, a citizen of the United States, residing at Atlanta, in the county of Fulton and State of Georgia, have invented new and useful Improvements in Toy Swings, of which the following is a specification.

This invention relates to toys and it has particular reference to a toy swing in which a doll may be placed, said swing being mechanically operated by means of a spring motor.

A further object of the invention is to produce a simple and improved toy swing which will be mechanically operated and which will not be liable to get out of order.

With these and other ends in view which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawing:—

Figure 1 is a front view of a swing constructed in accordance with the invention.

Fig. 2 is a vertical sectional view taken on the line 2—2 in Fig. 1.

Fig. 3 is a horizontal sectional view taken on the line 3—3 in Fig. 1.

Corresponding parts in the several figures are denoted by like characters of reference.

A pair of uprights 15 supported on a base 16 are connected together and spaced apart at their upper ends by a cap piece 17 having eyes 18 connected with the under side thereof. The body S of the swing is swingingly supported from the eyes 18 by means of yokes 19, said swing body having arm rests 20 and a bottom member 21 through which the limbs of the yokes 19 extend, the lower extremities of the limbs being bent upon or otherwise made fast to the bottom member, it being understood that the said yokes are constructed of moderately stiff wire, the front and rear limbs

22 and 23 being preferably made to diverge 55 in a downward direction.

A motor which may be of any desired type, although a simple spring motor may be preferred, is mounted within a casing M, said motor having been shown as including 60

a winding post 24 and a driven shaft 25. The motor casing is mounted on one of the uprights 15. Fixed on the cap piece 17 are brackets 26 forming bearings for a shaft 27 having cranks 28 that are positioned between the front and rear limbs of the yokes 19. Motion may be transmitted through the driven shaft 25 to the crank shaft 27 in any convenient manner; in the drawing the driven shaft has been shown as carrying a 70

spur wheel 29 meshing with a pinion 30 on the crank shaft. It is obvious that when the latter is rotated the cranks will alternately engage the front and rear limbs of the yokes 19, whereby the swing body is 75 suspended, thereby imparting a vibratory movement to the swing. Pivoted on the front limb of one of the yokes 19 is an arm 31 having a resilient catch 32 adapted to engage the front limb of the other yoke, 80 thereby retaining in position a doll or image D supported in the swing body.

When a spring motor is used, the cranks 28 coöperate with the yokes 19 to constitute an escapement, whereby the operation of the 85 motor is to some extent controlled, it being readily understood that when the cranks become disengaged from contact with the limbs at one side of the yokes the crank shaft will be temporarily speeded until the opposite 90 limbs are encountered when the speed will be retarded, thereby checking the speed of the motor.

What is claimed is:—

1. A supporting frame, a swing body, 95 yokes whereby the body is swingingly supported, said yokes having front and rear limbs, a shaft extending between the front and rear limbs, cranks on the shaft alternately engaging the front and rear limbs, 100 and means for driving the shaft.

2. In a toy of the class described, a pair of uprights and a cap piece connecting the same, eyes extending downwardly from the cap piece, yokes engaging the eyes, said yokes having front and rear limbs, a swing body supported by the yokes, bearings extending downwardly from the cap piece, a 105

shaft supported in said bearings and extending between the front and rear limbs of the yokes, said shaft having cranks alternately engaging said front and rear yokes, and 5 means for driving the crank shaft, including a motor supported on one of the uprights.

3. In a toy of the class described, a supported frame, including a cap piece, a 10 swing body having arm rests and a bottom member, yokes swingingly supported by the

cap piece and having front and rear limbs extended through the arm rests to the bottom member, said limbs being made fast to the bottom member, an arm pivotally connected on the front limb of one yoke and having a resilient catch for engagement with the front limb of the other yoke, and means for imparting swinging motion to the yokes.

15 In testimony whereof I affix my signature.

CARL ABERNATHY.
